QUILTING FRAME

Hugh B. Donnelly, Tarentum, Pa.

Application April 12, 1933, Serial No. 665,703

3 Claims. (Cl. 45—24)

This invention relates to quilting frames and more in particular to folding quilting frames adapted for quilting bed spreads or similar articles.

5 The primary object of this invention is to provide a quilting frame which can be folded up into a very compact and limited space, when not in use.

Another object is to provide such a device which 10 can be assembled or folded very quickly.

A further object is to provide a device which is adapted for quantity manufacture in wood.

15 Additional features and advantages of this invention will appear from the following description considered in connection with the accompanying drawing forming a part of this application and in which:—

Figure 1 is a front elevation of the device showing the quilting frame set up, ready for use.

20 Figure 2 is a side elevation of Figure 1.

Figure 3 is a top elevation of the quilting frame. Figure 4 is an isometric view of the female portion of one of the quilt supporting bars.

25 Figure 5 is an isometric view of the male portion of one of the quilt supporting bars.

Figure 6 is a representation of one of the side frames in folded condition, and

Figure 7 represents an isometric view of the hinged portion of the side frame.

30 Referring to the drawing, the quilting frame comprises a pair of foldable side frames 1, a pair of interlocking quilt supporting bars 2 and an interlocking retaining bar 3.

The foldable side frame 1 consists of a cross-bar 4, supported on, and hingedly connected ad-

35 jacent its ends, to the legs 5 by means of hinge-plates 6, which latter, are held in a slot 7 and swingingly supported on a screw or pin 8. Screws 9 may be employed to hold the other end of said hinge-plate on said legs 5.

The quilt supporting bars 2 and the retaining bar 3 are of the same construction and consist of two parts, the male portion 10 and the female portion 11.

40 The male portion 10 is composed of a bar 12 of H-shaped cross-section having inserted in the recesses 13 substantially square bars 14, rigidly held together by nails or screws. By this construction a cruciform design of the quilt supporting bar 2 and the retaining bar 3 is obtained, the purpose 45 of which will be described later.

As will be noted in Figure 5 of the drawing, the free end 15 of the male portion 10 is provided with a centrally disposed wing-bolt 16, and the 50 same may be prevented from turning when loos-

ening or tightening by any suitable means, such as a T head which is imbedded in the bridge 17 of H bar 12. The outer end 18 of the H bar 12 must be flush with the square bars 14 when assembled. As shown in Figure 5 of the drawing, the H bar 12 is considerably longer than the square bars 14, so as to provide an open space between said square bars 14.

Referring now to Figure 4, the female portion 11 of the supporting or retaining bars 2 and 3 respectively, consists of two parallelly disposed square bars 20, imbedded and securely nailed or screwed in the recesses 21 of the H bar 22 in the same manner as heretofore described for the male portion 10, the only difference being in that the lengths of the H and square bars are reversed, that is, the square bars 20 are considerably longer than the H bar 22. The inner ends 23 of said square bars 20 are provided with a cut-out portion 24 which comes in engagement 55 with the under-cut portion 25 of the male portion of the quilt supporting bar 2 or the retaining bar 3, when in closed position. This joint will be well suited for supporting the quilting material without sagging.

In use, the male and female portions of the quilt supporting bar 2 or the retaining bar 3 are put together, by sliding the H bar 12 of the male portion between the open space of the square bars 14 of the female portion 11 until the H bar 12 comes in abutment with H bar 22. Both, the male and the female portions are held in locked position by means of a hook connector 26 of any desired commercial design.

The engaging parts of the male and female portions 10 and 11 respectively are suitably dimensioned to provide sufficient clearance to allow normal engagement, without sacrificing the rigidity of the same when put together for use.

The quilt supporting bars 2 and the retaining bars 3 may be of any desired length to suit the width of the quilting material.

The legs 5 are suitably apertured at 27 for the reception of the wing-bolts 16, by which means they are held together.

When using the quilting frame, the wing-nut bolts 16 of the quilt supporting bars 2 are inserted in suitable slots 28 provided adjacent the ends of the cross-bars 4 for that purpose and are then securely held from rotation by means 105 of wing-nuts 29.

The ends of the quilting material are then nailed on one of the four arms or nailing strips 30 of the cruciform shaped bar 2 and rolled up until the quilting material is fully stretched.

110

As the work progresses the material is rolled up on one of the quilt supporting bars and released from the other quilt supporting bar by loosening the wing-nuts 29. When the quilting material is again fully stretched the wing-nuts 29 are again tightened.

When the device is not in use, all folded parts are placed together and tied with a strap or rope; when so packed the quilting frame requires very little space and can be easily stored away for future use.

Many changes in the precise construction, arrangement and combination of the various parts may be made without exceeding the scope of the claims, and I reserve the liberty of making all such changes as may be thought desirable and come within the scope of the appended claims.

I claim:—

1. In a quilting frame of the character described, a pair of foldable side elements provided with legs, a pair of separable quilt supporting bars and a separable retaining bar, said separable quilt supporting bars and said separable retaining bar composed of a male and a female member; said male member comprising an elongated H-bar and a short square bar imbedded adjacent the end of said H-bar in each of the recesses of the latter, said female member comprising a pair of elongated parallelly disposed square bars, each imbedded adjacent its ends in one of the recesses of a short H-bar, said short square bars of said male member having at its abutting ends an under-cut portion adapted to register with a cut-out portion of the square bars of said female member, the latter also adapted to receive therebetween said elongated H-bar of said male member, and means for locking said male and female member after uniting.

2. In a quilting frame of the character described, a pair of foldable side elements provided with legs, a pair of separable quilt supporting bars and a separable retaining bar, said separable

quilt supporting bars and said separable retaining bar composed of a male and a female member; said male member comprising an elongated H-bar and a short square bar imbedded adjacent the end of said H-bar in each of the recesses of the latter, said female member comprising a pair of elongated parallelly disposed square bars, each imbedded adjacent its ends in one of the recesses of a short H-bar, said short square bars of said male member having at its abutting ends an under-cut portion adapted to register with a cut-out portion of the square bars of said female member, the latter also adapted to receive therebetween said elongated H-bar of said male member, and means for locking said male and female member after uniting.
